ASH RECEIVER

William J. Merz, Detroit, Mich.

Application May 20, 1936, Serial No. 80,851

13 Claims. (Cl. 131—51)

This invention relates to ash receivers and similar devices, and more particularly to a receiver of the type having hinged closures on which ashes may be deposited, but which are adapted to swing inwardly to dump the ashes into the receptacle.

One of the objects of the invention is the provision of a hinged closure which is held in position to receive ashes and cigarette stubs by a cover or cigarette supporting member, the latter being removable to permit the closure to fall by its own weight and thereby dump ashes into the receptacle.

It is another object of the invention to so form the several parts that the receiver is easy to manufacture and is relatively inexpensive.

Other objects of the invention will be apparent from the following description thereof when taken with the appended drawing, in which—

Fig. 1 is an elevation, partly in section, of the ash receiver, taken on lines 1—1 of Figure 2;

Fig. 2 is a top view, partly in section, of the receiver shown in Fig. 1;

Fig. 3 is a side view taken on lines 3—3 of Figure 1, the parts thereof being sectional, of the top of the receiver;

Fig. 4 is a top view of a stamping from which one part of the closure is formed, and

Fig. 5 is a fragmentary sectional view showing the cover lifted with respect to the receptacle.

In the drawing, the receiver comprises a bowl shaped base or receptacle 10 and an upper annular member 11 preferably detachably connected to the base as by a bayonet joint indicated at 12, although the parts may be held together by a frictional fit if desired. In the form shown in the drawing, both the base and annular member are shaped from sheet metal. The upper or top piece 11 is formed with a substantially circular horizontal flange 13, the inner periphery of which has opposite straight chord-like edges 14. Parallel with edges 14 on each side of the receiver top are openings 15, preferably cut out in such a manner that the metal at the ends of the openings may be bent under and looped to form a hinge pin housing 16.

The closure 17 is formed from a pair of plates 18, 18' having their opposed edges 19, 19' abutting along a diametrical line and fashioned at their opposite sides to form one part of the hinge for each plate. As shown in Fig. 4, each plate has a main, substantially semi-circular portion 20 and an extension of generally trapezoidal form indicated at 21. The lateral wings 22 are first bent at a right angle to the plane of the plate

along the dotted lines 23, after which the extension is also bent at a right angle to the said plane along the dotted line 24, bringing the edges 25 of the wings into abutting relation with the bottom surface of the semi-circular portion of the plate. Apertures 26 are punched in the wings and accommodate a U-shaped pin 27, the legs 28 of which are held in the loops or bearings 16.

The plates, because they are unbalanced, tend to fall or tilt downwardly, in which position the closure of the receiver would be open. To hold the plates in normal cooperative closing relation, a removable ring-like cigarette support 29 having lugs 30 on the under side thereof rests on the top of the receiver. Lugs 30 are oblong in longitudinal section and fit fairly snugly in openings 15 in the top of the receiver. The transverse section of each lug is shown in Fig. 1, from which it will be seen that the inner face thereof is vertical, while its rear face is rounded to permit easy insertion of the lugs in openings 15. The lugs are so spaced from each other that, as they are inserted, they first engage the extensions 21 and then rock each plate about its hinge pin to bring the main or closure portions of the plates 18, 18' to the horizontal and receiver closing position shown in Fig. 1. At this time the inner face of each lug engages and lies flush against the angularly bent extensions on the respective plates, thus holding the main portions of the plates in elevated position and with their edges in abutting relation, so that they will support ashes and stubs deposited thereon.

Disposed above the closure members and secured either to the receiver top 11 or to the supporting ring 29 is a wire member 31 having an upwardly projecting and return bent portion 32. This projection may be used either to support cigarettes in conjunction with recesses 33 in ring 29, or to aid in the removal of ashes or lighted ends from cigarettes.

When it is desired to dump the ashes and stubs into the receptacle, the ring 29 is lifted above the top of the receiver sufficiently to draw lugs 30 from engaging relation with the extensions on the closure plates. These plates will then tilt, since the main portion of each plate is substantially larger and heavier than the extension, permitting matter held thereon to fall into the receiver, as shown in Fig. 5.

The various parts shown in the drawing are preferably pressed or spun from sheet metal, although it is intended that glass, molded phenol condensates, and other materials may be used if desired. It is apparent that the receiver com-

prises but few parts, all of which are easily fabricated, thus permitting its manufacture at little expense and with few operations. The embodiment shown in the drawing is merely illustrative of a preferred arrangement, and it is intended that the invention be susceptible of modification.

What I claim as my invention is:

1. An ash receiver, comprising an open receptacle, a hinged closure plate therefor, and a removable member on said receptacle, said member being engageable with said plate to hold the plate in receiver closing position.
2. An ash receiver, comprising an open receptacle, a pair of opposed hinged closure plates therefor, the opposed edges of said plates being in abutting relation, and a removable member on said receptacle engageable with said plates to hold the plates in receiver closing position.
3. An ash receiver comprising an open receptacle, a hinged closure plate therefor, said plate being hinged along one edge thereof and having an extension adjacent said edge, and a removable member on said receptacle engageable with said extension to hold the plates in receiver closing position.
4. An ash receiver comprising an open receptacle, a closure plate therefor, said plate comprising a receiver closing portion and an extension angularly disposed thereto, means for hinging said plate to said receptacle intermediate said portion and said extension, and a removable member on said receptacle engageable with said extension to hold said portion in receiver closing position.
5. An ash receiver comprising a receptacle having an open end, a closure plate therefor, said plate having a receiver closing portion and an extension thereon, said extension being substantially lighter in weight than said portion, means for hinging said plate intermediate said portion and said extension whereby said plate is unbalanced about its hinge, and a removable member mounted on said receptacle and engageable with said extension to hold said plate in receiver closing position, said portion being tiltable inwardly when said member is removed.
6. An ash receiver comprising a receptacle having an open end, a closure plate therefor, said plate having a receiver closing portion and an extension thereon, said receptacle having an inward peripheral flange about its open end, said flange having an opening therein, a hinge pin housing adjacent said opening, a hinge pin cooperating with said pin housing and with said plate intermediate said portion and said extension, and a removable member mounted on said receptacle and engageable with said extension to hold said plate in receiver closing position, said portion being tiltable inwardly when said member is removed.

7. An ash receiver comprising a receptacle having an open end, a closure plate therefor, said plate having a receiver closing portion and an extension thereon, said receptacle having an inward peripheral flange about its open end, said flange having an opening therein, a removable member mounted on said member insertable through said opening to engage said extension and hold said plate in receiver closing position. 5

8. An ash receiver comprising a receptacle part having an open end, a hinged closure plate therefor, a movable part seated on said receptacle, said last mentioned part being engageable with said plate to hold the plate in receiver closing position, and ash removing means on one of said parts and disposed above said closure plate. 10

9. An ash receiver comprising a receptacle part having an open end, a hinged closure plate therefor, a movable part seated on said receptacle, 20 said last mentioned part being engageable with said plate to hold the plate in receiver closing position, and a wire member supported on one of said parts and disposed above said closure plate. 25

10. An ash receiver comprising a receptacle having an open end, a closure member hingedly supported on the receptacle and normally in an open position, a member removably seated on the open end of the receptacle engageable with 30 the closure to hold the same in closed position and effective upon upward movement thereof to release the closure member.

11. An ash receiver comprising a receptacle having an open end provided with an inwardly 35 extending flanged portion, a hinged closure plate with an extension thereon mounted on said portion, a removable member on said portion engageable with said extension to hold the plate in receiver closing position.

12. An ash receiver comprising a receptacle having an open end, an upper inwardly flanged portion about the open end, said flange having an opening therein, a hinged closure plate with an extension thereon mounted on said portion, a 45 removable member mounted on said receptacle and means on said member insertable through said opening to engage said extension to hold the plate in receiver closing position.

13. An ash receiver comprising a receptacle 50 having an open end provided with an upper inwardly flanged portion having slots therein, a pair of hinged closure plates having angularly disposed extensions hingedly mounted near said slots, a removable member having lugs insertable 55 through the slot and engageable with the extensions to hold said plates in receiver closing position, said plates being tiltable inwardly by disengagement of the lugs from the extension. 60
